[57] CLAIM

The ornamental design for a combined earphone and remote controller, as shown and described.

DESCRIPTION

FIG. 1 is a top, front and right-side perspective view of a combined earphone and remote controller, showing our new design;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof; and,
FIG. 7 is a bottom plan view thereof.

The cord member has been shown in fragment in the figure drawings to indicate undetermined length.

FIG. 1

FIG. 4

FIG. 5

FIG. 7
